UNITED STATES PATENT OFFICE.

LOUIS R. HORTON, OF PROVIDENCE, RHODE ISLAND, ASSIGNOR TO J. B. & S. M. KNOWLES, OF SAME PLACE.

DESIGN FOR A HANDLE FOR SPOONS, &c.

SPECIFICATION forming part of Design No. 20,594, dated March 24, 1891.

Application filed February 5, 1891. Serial No. 380,359. Term of patent 7 years.

To all whom it may concern:

Be it known that I, LOUIS R. HORTON, a citizen of the United States, residing at Providence, in the county of Providence and State 5 of Rhode Island, have invented and produced a new and original Design for Handles, of which the following is a specification, reference being had to the accompanying drawings, forming part thereof.

Figure 1 is an obverse view of a spoon and the handle thereof. Fig. 2 is a reverse view of the same.

The leading features of my design for handles of spoons, &c., consist in a symmetrical wave-like outline forming, with the gradually increasing width, alternating enlargements and contractions in the width of the handle, a scroll traced and extending from the side of the smallest enlargement, foliage 15 traced around such scroll and extending along the contracted neck of the handle, and a foliated scroll-border traced around the second and third enlargements and the intervening contractions and meeting at the top 20 of the handle in a scrolled leaf ornament.

3 in the drawings designates the bowl of a spoon. It may, however, be the bowl of a handle or the tine portion of a fork.

4 indicates the handle. The narrow portion or neck of the handle at 5 is curved outward on both sides of the handle in opposite directions to the point 6, where it commences to curve inward to 7, thence it again curves

outward to 6', then inward to 7', outward to 6'', and thence curving inward to the scrolled leaf ornament 8, forming the upper end of the handle, the width of the handle increasing symmetrically from 5 to 6'.

From the edges of the enlargement 6 the scroll 9 is traced inward toward and around the center of the enlargement, and this scroll 9 is surrounded by the foliage 9', which extends part way along the narrow contraction or neck 5. The foliated scroll-border 10 is traced, extending from the enlargement 6 40 around the edges of the enlargements 6' and 6'' and contractions 7 and 7' and curves inward at the upper end of the handle to meet the scroll-leaf ornament 8.

The back of the handle presents the symmetrical wave-line gradually increasing the width of the handle, with a border 11 extending from the foliage 12 on the bowl of the spoon or tine portion of a fork parallel to the outline, the ends of the scrolls 13 being traced 55 inward from the edges and meeting at the upper end of the handle in the foliage 8', traced partially on the ornamented projection 8.

What I claim is—

The design for handles of spoons, forks, &c., as herein shown and described.

LOUIS R. HORTON.
